Joseph A. C. Galvao, Brooklyn, N. Y.

Application July 2, 1936, Serial No. 88,517

3 Claims. (Cl. 173—358)

My present invention relates to a lamp socket or similar structure, adapted to cooperate with an Edison or screw plug, such as is used on the ordinary electric bulb or electric plug.

5 It aims to devise a construction, which while cheap in construction and simple of operation, will enable such an Edison plug or the like to be attached to the socket, without the necessity of laboriously screwing the same thereon. Using the 10 device of my present invention, an Edison plug or bulb can be inserted in the socket in but two simple movements; one, a pressure inward, and two, a slight clockwise turn.

The device of my present invention has a particular value in electric signs and marquises, where there are a large number of bulbs to be inserted and changed, and where the saving in time, which will result from using my present invention, will be substantial.

20 Further advantages and superiorities of my present invention will, in part, be hereafter pointed out and will, in part, be obvious to those skilled in the art to which the present invention relates.

25 In the drawing:—

Fig. 1 is a top plan, partly broken away; and Fig. 2 is a vertical sectional view.

Referring more specifically to the drawing, at 10 is shown the base proper, having a shell 11, adapted to receive the conventional or screw plug.

At 12 is shown a copper or other conducting metal strip, affixed to the base 10 by the screw 13, and to the shell 11 by the bent portions of the wire 14.

35 This wire 14 surrounds the shell 11, being contained in a recess 15, and in electrical contact with the metal strip 12 and the dogs 15 hereafter to be described.

At 16 is another metal band, also affixed to the 40 base 10 by the screw 17, and penetrating through the shell 11 to form the other point of contact 18' with the Edison or screw plug.

The dogs 15 comprise an upper and lower portion, 18 and 19, pivotally mounted about the wire 14, by means of the spring wire 20. The lower portions 19 of these dogs 15 are of uniform size, and project into the interior of the shell to cooperate with the tip of the Edison or screw plug.

50 The upper portions 18 of the dogs 15 also project into the interior of the shell, but these upper portions are of different sizes, so that the height of each of these upper portions will vary with the pitch of the thread of the Edison plug, the sizes 55 decreasing in a clockwise direction. It will be

seen that the inner sides of these dogs 15 form a sort of half-moon.

The spring wire 20 may be readily affixed to the upper portions 18 of the dogs 15 by having the upper portions 18 slit open, inserting the wire 5 within such slit, and thereafter pinching the sides together.

There may also be provided an outer covering 21, which may be threadedly engaged about the shell 11, at the threads 22.

10 In operation, the Edison plug 23 is inserted into the shell, until the lower portion thereof, shown at 24, has passed the lower portions 19 of the dogs 15, forcing the lower portions towards the shell 11 and the upper portions 18 inwardly away 15 from the shell, and in position to engage the threaded portions 25 of the Edison plug 23. At this point the tip 26 of the Edison plug 23 will be in contact with the contact point 18' of the band 16. The Edison plug 23 is then rotated 20 slightly in a clockwise direction, the upper portions 18 of the dogs 15 thus engaging the plug 23 at the threaded portions 25 and holding the same firm.

The electric current may enter the device 25 through the wire 21, which is connected to the band 16 by the screw 17, flow along the band 16 to the contact point 18', thence to the tip of the Edison plug 26, thence through the filaments, and return by means of the threaded portions 25, 30 the upper portion of the dogs 18, the wire 14, the band 12 and the return wire 28 which may be connected by the screw 13.

When it is desired to remove the plug, it is given a small counter-clockwise turn, thus releasing the engagement of the upper portions of the dogs 18, and the plug may then be pulled out. When the pressure on the lower portion of the plugs 19 is released, because of the withdrawal of the Edison plug 23, the wire 20 pressing against 35 the inner surface of the shell 11 will rotate the dogs 15 so that the upper portions thereof are now hidden in the recesses 29, leaving the device 40 ready for the insertion of another plug.

While the drawing illustrates three (3) dogs, it 45 is obvious that there may be more or less. I have found, however, that less than three (3) will not be as efficient.

The foregoing description of my present invention is set forth by way of illustration only, and 50 various modifications may be made therein without departing from the spirit thereof or the scope of the claims.

What I claim as my invention is:

1. In a socket for receiving a screw plug, a 55

shell, and a plurality of dogs pivotally mounted on a common plane in said shell thereof, said dogs having gripping portions at different levels above the pivot points to cooperate with the inclined thread of the screw plug, and contact portions below the points of pivot to be engaged by the screw plug base, whereby the insertion and turning of the screw plug in said shell causes the lower portion of said dogs to retreat, and the upper portion to project inwardly and engage the thread of the screw plug.

2. A socket for receiving a screw plug comprising a base, a plurality of dogs, a shell having a plurality of recesses adapted to contain the dogs and a recess about the outer side to contain a wire, said dogs being pivotally mounted within the recesses and about the wire on a common plane and having gripping portions at different levels above the points of pivot to cooperate with

the inclined thread of the screw plug and contact portions below the points of pivot to be engaged by the screw plug base, a spring wire affixed to the outer side of the upper portions of said dogs and adapted to be placed against the inner wall of said shell and means to complete the electric circuit.

3. In a socket for receiving a screw plug, a shell, and a plurality of pivotally mounted dogs in said shell, each of which has a thread riding and gripping end, and an operating end the thread riding and gripping ends occurring at different levels and the operating ends occurring at the same levels; whereby the insertion and rotation of the screw plug in said shell acts upon the operating ends to pivot said dogs and cause the engagement of the riding and gripping ends thereof with the threads of the screw plug.

JOSEPH A. C. GALVAO.
